(57) **CLAIM**

The ornamental design for a single-cam compound bow, as shown and described.

DESCRIPTION

FIG. 1 is a rear perspective view of a single-cam compound bow as viewed obliquely from the right behind the bow.

FIG. 2 is a left side elevation view of the single-cam compound bow with the bowstring cable undrawn.

FIG. 3 is a right side elevation view of the single-cam compound bow with the bowstring cable undrawn.

FIG. 4 is a left side elevation view of the single-cam compound bow with the bowstring cable drawn.

FIG. 5 is a right side elevation view of the single-cam compound bow with the bowstring cable drawn.

FIG. 6 is a front elevation view of the single-cam compound bow.

FIG. 7 is a rear elevation view of the single-cam compound bow.

FIG. 8 is a top plan view of the single-cam compound bow.

FIG. 9 is a bottom plan view of the single-cam compound bow.

FIG. 10 is a left side elevation view of the single-cam compound bow with the bow-limb bolt adjusted for a low draw-weight (force) with the bowstring cable undrawn; and,

FIG. 11 is a left side elevation view of the single-cam compound bow with the bow-limb bolt adjusted for a high draw-weight (force) with the bowstring cable undrawn.
